WATER GOING LINE CARRIER

Paul F. Still, Santa Clara, Calif., assignor to Avocation Products, Santa Clara, Calif., a corporation of California

Filed Dec. 9, 1960, Ser. No. 75,011
20 Claims. (Cl. 115—6.1)

This invention relates to a motor driven vessel and control means therefor and more particularly to certain novel improvements therein.

Various types of devices have been proposed heretofore for towing fish lines or the like along the surface of water. A few of these devices have control means for affecting steerability and others disclose means for controlling the drive. While these devices are effective for the purpose intended the first entails dual lines operable by the user to facilitate right and left directioning and the others require an additional line for controlling, more particularly stopping, the drive means. Moreover, this last mentioned drive control is effective only after the device is preset to drive the craft forward and once this has been changed by the control means forward motion cannot be re-established without drawing the device back to the user so that he can again preset it.

The present invention has as its principle object to provide in line towing devices a programmer facilitating a control cycle which can be repeated by manipulation of a single control line. In connection with this object it is a further object to provide a single means within the sealed vessel for accomplishing drive, stop and steerability by manipulation of but a single control line.

It is another object of this invention to provide an electrically operated, battery driven, compact line carrying device adapted to be self propelled along the surface of water. In connection with this object it is an object to provide such a device with a forward drive or propeller and a self sealing drive shaft driven from within the craft.

It is another object to provide in a puller type propeller arrangement for such craft, a forwardly extending drive housing having a course directing curved contour relative to fore and aft so as to compensate for or overcome drift due to prevailing water conditions and currents.

In connection with the foregoing object it is another object to provide in a craft of the type herein described, a novel means for excluding the intake of water along the drive shaft without the use of packing.

It is another object of the present invention to provide means in the form of a stabilizing fin for counteracting torque created by the propeller.

Another object is to provide braking means which normally assume non-braking condition during forward motion of the device in water and which automatically affords a braking action or resistance to backward movement of the vessel when such movement occurs upon manipulation of the control line.

These and other objects and advantages of the present invention will become apparent in the following description when read in the light of the drawings in which:

FIG. 1 is a longitudinal section through a self propelled line puller embodying the present invention.

FIG. 2 is an elevational view of the aft end of the craft as seen from the left in FIG. 1.

FIG. 3 is an enlarged transverse section through FIG. 1 taken substantially along line 3—3 in FIG. 1.

FIG. 4 is an enlarged fragmentary detail section of the aft compartment of the craft as seen in FIG. 1 showing the control means therefor.

FIG. 5 is a plan view of the aft portion of the craft

2

and its rudder, parts being broken away for purposes of illustration; and

FIG. 6 is an enlarged detail section of the propeller, screw, drive shaft and housing at the fore end of the craft.

Referring to FIG. 1 the line puller or craft, generally designated 10, comprises a vessel 11 having a sealed chamber 12 within which is carried a motor M, a source of power in the form of batteries B—B; a control means C including a switch S for closing a circuit D between the batteries and the motor and a programmer P for effecting a cycle of operation later to be explained.

The motor M which is at the fore end of the compartment or chamber 12 has a drive shaft 13 extending forwardly therefrom through a housing 14 and connected to a propeller 15 at the forward extremity thereof.

The control means C which is at the aft end of compartment or chamber 12 has one end of a manually operable control line 16 extending rearwardly therefrom through a rudder R. The opposite end of the control line 16 is in possession of the operator or user of the craft 10 and may be reeled up on a winch or other suitable means such as a fishing reel (not shown).

The batteries B which are of lesser diameter than the vessel 11 are secured in clips 17 in contact and alignment with each other within a frame 18. The frame 18 is secured at the base or keel line of the vessel so as to provide ballast therefore assuring buoyancy of the craft on a desired plane.

The vessel 11 is in the form of a tube 20 having a rounded fore end 21 terminating in a cylindrical neck 22. The aft or normally open end 23 of the tube 20 has an outwardly extending flange 24. A cap-like cover 25 is stretch fitted over the flange 24 to close the open end 23 of the tube in a water tight manner.

As best seen in FIGS. 1 and 5 the cap-like cover 25 is formed as a part of the rudder R, the entire body of which is resilient, it being made of relatively stiff but pliable, yieldable material such as rubber or any one of the well known polyester materials of like character which tends to assume its normal form and shape. This forms a part of the steering means of the present invention and will therefore be explained in detail hereinafter.

As best illustrated in FIGS. 1, 3, 4 and 5 the control means C is secured in place within the tube or vessel 11 on an aft part of the frame 18. To this end a rearward extension 26 of the frame 18 is bent up slightly from the floor of the tube 20. A bolt 27 extending through the extension 26 serves to secure a back plate 28 to the frame 18. This provides a ground contact for the aft battery, and a trunnion bracket 29 for the programmer P. The back plate 28 is a metal stamping from which a lower foot portion 30 extends rearwardly over and in contact with the rearward extension 26 of frame 18. A leaf spring arm 31 overlies the foot portion 30 and is secured with the latter to the rearward extension 26 by the bolt 27. As best seen in FIG. 4 the bolt 27 is insulated from the frame 18, foot 30 and leaf spring 31 to provide one contact of the switch S. The leaf spring 31 is formed so as to overlie the round head top 32 of the bolt 27 and thereby forms the other contact of the switch S. Also insulated from the frame 18 but in electrical contact with the bolt 27 is a conductor tab or washer 33 which has one end of an electrical conductor wire 34 soldered thereto. This wire 34 meanders forwardly within the tube 20 and has its opposite end soldered to one lead of the electric motor M. The other lead of motor M is connected to a conductor 35 having its opposite end soldered to a center contact 36 secured to an upturned fore end 37 of the frame 18 and insulated therefrom in a conventional manner. This foregoing constitutes the circuit D under the con-

trol of the switch S for energizing the motor M upon closing of the switch or for shutting off the motor when the switch is open.

Closing and opening of the switch S is effected by the programmer P which is manually operated by the control means C under the influence of the control line 16.

The trunnion bracket 29 comprises a pair of arms 38 and 39 bent back from the back plate 28 of which they are a part. These arms 38-39 are spaced from each other, equidistant from axial center of the tube 20 and have a pinion shaft 40 journaled at their ends substantially transverse to the said axis. A step-up mechanism in the form of a ratchet and cam unit 41 is mounted on the shaft 40 for step by step turning relative thereto. One side of the unit 41 has diametric grooves 42 within which a kinked portion 43 of the adjacent arm 39 of the cam seat to provide means for holding the ratchet and cam unit at predetermined positions other than when the ratchet is turned. It will be noted that the end of shaft 40 extends through and beyond the arm 39 so that the arm 39 can flex outwardly during turning of the unit 41.

The unit 41 has a dual ratchet 44-44', one on each side of a central cam 45 which is operatively associated with the switch arm end 46 of the leaf spring 31, previously mentioned. As best seen in FIG. 4 this end 46 of the leaf spring tends to bear against the cam 45 and to be pressed downwardly by the high side of the same to hold the switch arm in circuit closing contact with the round head of the bolt 27, the other contact of switch S.

In the present disclosure the ratchets 44-44' have four aligned teeth quadrantly disposed. Within one of these quadrants IV is a declivity 47 of the cam 45, the declivity being of such depth radially as to allow the leaf spring arm 31 to rise, due to its own resiliency. In this manner the leaf spring contact 31 moves away from the round head of the bolt 27 to open the switch S and thereby cut off flow of current from the batteries B-B to the motor M. This would constitute the last or normal position of the switch when the vessel is not in use. To start the motor M the ratchets 44-44' must be moved at least one step (one quadrant) to dispose the high side of the cam 45 in contact with the switch arm 31 to press the latter against the bolt head 32 to close the switch S. Since the high side of the cam extends three quadrants (3/4), the circumference the switch will remain closed until quadrant IV is again positioned to dispose the declivity thereof in contact with the leaf spring 31.

The ratchets 44-44' are operatively associated with a pawl 48. This pawl is broader than the cam 45 so as to span the latter and engage the teeth on opposite sides thereof as illustrated in FIGS. 3 and 5. The pawl 48 is a downturned end on a flexible paddle shaped base 49 having its fore end secured to a rod 50. This rod 50 extends through a pair of aligned openings 51-52 formed in the legs 53-54 respectively of a U-shaped guide frame 55 formed as a part of the back plate 28. The rod 50 has a compression spring 56 thereon between the legs 53-54 of the U-shaped guide frame 55. This spring 56 has its aft end bearing against the aft leg of the frame 55 and its fore end bearing against a washer 57 mounted on the rod 50 and blocked against forward movement relative thereto by a cotter pin 58. In this manner, the rod 50, and with it the pawl 48, is urged forwardly relative to the guide frame 55, to the position shown in FIG. 1. This forward movement is limited by a flange head 59 at the juncture of the rod with the paddle base 49.

As best seen in FIGS. 1 and 4 the control line 16 is secured to the paddle base 49. When the control line 16 is pulled rearwardly the paddle 49, pawl 48 and rod 50 are drawn rearwardly to the position shown in FIG. 4 against the action of the spring 56. In this manner

the pawl 48 is drawn over the top quadrant teeth of the ratchets 44-44', the latter being held stationary by the ratchet holding means (groove 42 and kinked portion 43 of the arm 39). Here it should be noted that the opening 52 in the aft leg 54 of the U-shaped guide frame 55 is a vertical slot so that the pawl 48 can rise as it glides over the arcuate teeth of the ratchet. Now when the control line is released the spring 56 expands to normal thereby pulling the pawl 48 forwardly into the position shown in FIG. 1. The pawl which was engaged behind the uppermost teeth of the ratchets 44-44' thereby turns the ratchet one quadrantal step.

Each quadrantal step of the ratchet establishes a particular phase of operation of the programmer P. For purpose of clarity the cycle of operation of the programmer P is as follows:

Step	Drive	Steering
I	Motor On	Rudder Dead Ahead
II	Motor On	Rudder Left
III	Motor On	Rudder Right
IV	Motor Off	Rudder Dead Ahead

The steering of the vessel is also controlled by the programmer. To this end the unit 41 has a pair of arms l and r carried by the right and left ratchets 44 and 44' respectively. These arms l and r are disposed to the sides of the pawl 48 and paddle 49 (FIGS. 3 and 5) so as to turn with the unit 41 in the spaces between the pawl 48-49 and the arms 38 and 39 of the trunnion 29. These arms l and r therefore turn freely with the unit 41 within the trunnion 29 and engage nothing except the cover 25 at the aft end of the tube 20 and then only when such arm l or r extends rearwardly from the trunnion.

The arm l which is on the left hand ratchet 44 is disposed in the quadrant II of the ratchets. When the control line 16 is pulled to advance the ratchet unit another step the arm r is the first to engage the cap or cover 25 as illustrated in FIG. 5. When this occurs the relatively stiff but pliable material from which the cover is made, flexes outwardly from the left side of the cover causing the rudder R to assume right rudder position as shown in full lines FIG. 5. This causes the craft or vessel to turn to the right.

The arm r which is on the right hand ratchet 44' is disposed in the next quadrant III of the ratchet. Hence when the control line 16 is pulled again and the ratchets advanced another step, the arm l disengages the cover 25 and the arm r now engages the cover but on the other (right) side of center (see dotted lines FIG. 5). Thus it will be seen that the rudder R, by its own resiliency returns from right rudder position to center and as the arm r engages the right side of the cover, the rudder R is flexed to the left of center (see dot-dash or left rudder position FIG. 5).

It should here be noted that throughout steps I, II and III the high side of the cam 45 is in engagement with the switch arm 31 to maintain the switch closed and the motor running. However upon the fourth pull on the control line 16 to advance the ratchet unit 41 another step (IV) the cam declivity 47 registers with the free end of the switch arm 31 releasing the latter, thereby causing the switch S to be opened (circuit breaking condition). This at one and the same time stops the propeller or forward drive of the vessel and simultaneously releases the rudder R for return to center position or dead ahead position. Consequently when the cable 16 is pulled again (a new cycle of operation of the programmer P) the ratchet unit steps up on quadrant to again dispose the high side of cam 45 against leaf spring 31 to close switch S and turn on the motor.

From the foregoing it will be appreciated that with but a single cord or control line (16) the drive means of the

vessel can be started and stopped and the vessel steered at the will of the person manipulating the control line.

As best seen in FIGS. 1, 2 and 5 the control line 16 extends through a central tubular section 60 of the rudder R. This tubular section 60 terminates in a reduced neck 61 which is cemented to a flexible tube 62 to provide a water seal. The tube 62 is long enough to assure a long surface seal between the inner walls of the tube 62 and the nylon leader which is the terminal end of the control line 16. In this manner a water tight seal is provided so as to prevent water from entering the chamber 12.

The body of the cylinder 20 has a stabilizing fin or keel 65 extending downwardly therefrom. This fin 65 is offset at an angle of approximately 5° to vertical to counteract torque created by the propeller 15. This fin 65 is far enough forward on the tube 20 to leave space for a brake 66. The brake 66 is a flat baffle plate hingedly connected as at 67 to the tube 20 transversely thereof and adjacent the aft end of the fin 65. The arrangement is such that during forward movement of the vessel 11 in water, the plate 66 will assume a horizontal position and glide through the water. However upon any backward movement of the vessel in the water, as when the control line 16 is pulled, the plate 66 will swing down into against the aft end of the fin 65 and thereby provide resistance and therefore a braking action to backward movement of the vessel in the water. Thus it will be appreciated that although the return spring 56 on the pawl arrangement requires a fair tug in order to step up the ratchet unit 41, the baffle plate 66 affords sufficient resistance to assure full stroke operation of the programmer each time the control line 16 is pulled.

Referring now to the fore end of the vessel as seen in FIG. 1 and detailed in FIG. 6, it will be noted that the drive shaft 13 is a twisted cable which fits snugly in a polyethylene tube 73 mounted with the housing 14. The fore-end of this cable 13 is suitably anchored in and secured to the hub of propeller 15. The propeller 15 rests against the fore end of the housing 14 but since it pulls the vessel forwardly there is a possibility of admittance of water into the tube 73 bearing the drive shaft 13. Although no packing is provided here it will be noted that the helical trend of the twisted cable 13 is such as to act as a screw pump which forces any incoming water forwardly and out of the tube 73.

As previously mentioned the housing 14 for the drive shaft 13 has a curved contour. Moreover, as seen in FIG. 1 the entire housing 14 is rotatable relative to the neck portion 22 at the fore end 21 of the vessel 11. This allows for 360° adjustment of the curved housing to compensate for torque of the propeller and to overcome water conditions such as side currents as for example when the device 10 is used in a stream.

As seen in FIG. 1 the housing can be set with its curved contour disposed upwardly to hold the propeller high or at water level. Should the craft tend to turn from straight forward even though the rudder is set for dead ahead, the housing can be turned into a position which will compensate for such tendencies of the vessel to go off course.

Should the device 10 be used in a stream, in order to overcome the cross currents or downstream flow, the housing 14 can be turned to any position necessary to compensate for such current conditions.

While I have described my improvements for a line towing device in specific detail it will be appreciated that it may be susceptible to modifications, alterations and/or variations without departing from the spirit of my invention therein. I therefore desire to avail myself of all modifications, alterations and/or variations as fairly come within the purview of the appended claims.

What I claim as new and desire to protect by Letters Patent is:

1. In a water going line carrier of the propeller driven type having a tubular body providing a sealed chamber confining a motor and a battery in a circuit with a switch

for controlling said circuit; a programmer within said chamber comprising a step-up mechanism having cam means alternately engageable with said switch for opening and closing the same, and a manually operated control line extending into said chamber and secured to said step-up mechanism for advancing the same.

2. In a water going line carrier of the propeller driven vessel type having the form of a sealed chamber confining a motor connected to the propeller and a battery in a circuit with the motor including a switch for controlling said circuit; a programmer within said chamber comprising a ratchet having cam means operatively engaging said switch for opening and closing the same, a spring urged pawl for advancing said ratchet in steps, and a manually operated control line entering the chamber of said vessel and secured to said pawl for pulling the latter against the action of its spring for advancing said ratchet.

3. In a water going line carrier of the propeller driven type having a tubular body providing a sealed chamber confining a motor and a battery in a circuit with a switch for controlling said circuit; a resilient rudder, a programmer within said chamber comprising a ratchet having cam means operatively engageable with said switch for opening and closing the same, a left and a right tiller arm spaced segmentally from each other on said ratchet and alternately engageable with said rudder for flexing the same to the left and the right respectively, a spring urged pawl for advancing said ratchet in segmental steps, and a manually operated control line extending into said chamber and secured to said pawl for pulling the latter against the action of its spring for advancing said ratchet.

4. In a water going line carrier of the type having a tubular body providing a sealed chamber confining an electric motor, batteries in circuit with the motor and a switch in said circuit for controlling the latter; a rudder at the aft end of said tubular body, a drive shaft housing at the fore end of said tubular body, a propeller at the fore end of said housing, a drive shaft connected to said propeller and said motor, and a programmer in said chamber comprising a step-up mechanism including a cam engageable with said switch for opening and closing the same, and a manually operated control line extending into said chamber and secured to said step-up mechanism for advancing the same to thereby engage and disengage said cam with said switch at the option of the user manipulating said control line.

5. In a water going line carrier of the type having a tubular body providing a sealed chamber confining an electric motor, batteries in circuit with the motor and a switch in said circuit for controlling the latter; a resilient rudder at the aft end of said tubular body, a drive shaft housing at the fore end of said tubular body, a propeller at the fore end of said housing, a drive shaft connected to said propeller and said motor, and a programmer in said chamber comprising a step-up mechanism including a cam engageable with said switch for opening and closing the same, a manually operated control line extending into said chamber and secured to said step-up mechanism for advancing the same to thereby engage and disengage said cam with said switch at the option of the user manipulating said control line, and tiller arms on said step-up mechanism spaced circumferentially of each other for alternately engaging and disengaging said resilient rudder for flexing the same to right and left alternately for changing the course of said water going carrier.

6. In a water going line carrier of the type having a tubular body providing a sealed chamber confining an electric motor, batteries in circuit with the motor and a switch in said circuit for controlling the latter; a rudder at the aft end of said tubular body comprising a resilient hollow tail-like fin, a propeller at the fore end of said body, a drive shaft connected to said propeller and said

motor, and a programmer in said chamber comprising a step-up mechanism including a pawl and ratchet, a cam on one segment of said ratchet engageable with said switch, when said ratchet is in one of its stepped positions, for opening and closing the same, a tiller arm on each of the next two segments of said ratchet and alternately engageable with said resilient hollow tail-like fin for flexing the latter right and left respectively, relative to said tubular body, and a manually operated control line extending through said hollow tail-like fin into said chamber and secured to said pawl for advancing said ratchet one segmental step each time the user manipulates said control line.

7. In a water going line carrier of the type having a tubular body providing a sealed chamber confining an electric motor, batteries in circuit with the motor and a switch in said circuit for controlling the latter; a rudder at the aft end of said tubular body comprising a resilient hollow tail-like fin, a propeller at the fore end of said body, a drive shaft connected to said propeller and said motor, and a programmer in said chamber comprising a step-up mechanism including a pawl and ratchet, a cam on one segment of said ratchet engageable with said switch when said ratchet is in one of its stepped positions for closing said switch, a tiller arm on each of the next two segments of said ratchet and alternately engageable with said resilient hollow tail-like fin for flexing the latter right and left respectively relative to said tubular body, a manually operated control line extending through said hollow tail-like fin into said chamber and secured to said pawl for advancing said ratchet one segmental step each time the user manipulates said control line, and a brake mechanism on said tubular body facilitating unrestricted forward movement thereof under the influence of said propeller and resisting backward movement of said body when pulled rearwardly upon manipulation of said control line.

8. In a water going line carrier of the type having a tubular body providing a sealed chamber confining an electric motor, batteries in circuit with the motor and a switch in said circuit for controlling the latter; a rudder at the aft end of said tubular body comprising a resilient hollow tail-like fin, a propeller at the fore end of said body, a drive shaft connected to said propeller and said motor, and a programmer in said chamber comprising a step-up mechanism including a pawl and ratchet, a cam on one segment of said ratchet engageable with said switch when said ratchet is in one of its stepped positions for closing said switch, a tiller arm on each of the next two segments of said ratchet and alternately engageable with said resilient hollow tail-like fin for flexing the latter right and left respectively relative to said tubular body, a manually operated control line extending through said hollow tail-like fin into said chamber and secured to said pawl for advancing said ratchet one segmental step each time the user manipulates said control line, a keel-like fin on said body and a baffle plate hinged on said tubular body transversely of said keel-like fin and free to glide through the water during forward movement of said body under the influence of said propeller and for abutting the aft end of said keel-like fin for resisting backward movement of said body when the latter is pulled rearwardly upon manipulation of said control line.

9. In a water going line carrier of the type having a tubular body providing a sealed chamber confining an electric motor, batteries in circuit with the motor and a switch in said circuit for controlling the latter; a rudder at the aft end of said tubular body comprising a resilient hollow tail-like fin, a propeller at the fore end of said body, a drive shaft connected to said propeller and said motor, and a programmer in said chamber comprising a step-up mechanism including a pawl and ratchet, a cam on one segment of said ratchet engageable with said switch when said ratchet is in one of its stepped positions for closing said switch, a tiller arm on each of the next two

segments of said ratchet and alternately engageable with said resilient hollow tail-like fin for flexing the latter right and left respectively relative to said tubular body, a manually operated control line extending through said hollow tail-like fin into said chamber and secured to said pawl for advancing said ratchet one segmental step each time the user manipulates said control line, a stabilizing keel-like fin on said body set at an angle of at least 5 degrees off vertical to counteract torque created by said propeller, and a baffle plate hinged on said tubular body transversely of said keel-like fin and free to glide through the water during forward movement of said body under the influence of said propeller and for abutting the aft end of said keel-like fin for resisting backward movement of said body when the latter is pulled rearwardly upon manipulation of said control line.

10. In a water going carrier having a tubular body providing a sealed chamber confining an electric motor, a battery in circuit with said motor and with a normally open switch for controlling said circuit; a step-up mechanism within said chamber having a cam movable into and out of engagement with said switch for closing and opening the latter, a control line operatively connected to said step-up mechanism for advancing the same when said control line is manually pulled, a drive shaft housing projecting forwardly from said tubular body including a passage, a propeller at the fore end of said housing, and a drive shaft connecting said propeller to said motor comprising a twisted cable snugly fit within said passage whereby the helical trend of said cable cooperates with the internal wall of said passage to force incoming water outwardly of said passage during rotation of said cable.

11. In a water going carrier having a tubular body providing a sealed chamber confining an electric motor, a battery in circuit with said motor and with a normally open switch for controlling said circuit; a step-up mechanism within said chamber having a cam movable into and out of engagement with said switch for closing and opening the latter, a control line operatively connected to said step-up mechanism for advancing the same when said control line is manually pulled, a drive shaft housing projecting forwardly from said tubular body including a passage, a propeller at the fore end of said housing, a flexible drive shaft connecting said propeller to said motor, said drive shaft housing having a curved contour diverging relative to the fore to aft axis of said tubular body for counteracting torque created by said propeller.

12. In a water going carrier having a tubular body providing a sealed chamber confining an electric motor, a battery in circuit with said motor and with a normally open switch for controlling said circuit; a step-up mechanism within said chamber having a cam movable into and out of engagement with said switch for closing and opening the latter, a control line operatively connected to said step-up mechanism for advancing the same when said control line is manually pulled, a drive shaft housing projecting forwardly from said tubular body including a passage, a propeller at the fore end of said housing, a flexible drive shaft connecting said propeller to said motor, said drive shaft housing having a curved contour diverging relative to the fore to aft axis of said tubular body for counteracting torque created by said propeller, said drive shaft housing being turnable relative to said tubular body facilitating setting of the curved contour of said drive shaft housing to compensate for drift and side currents in the water in which said vessel is traveling.

13. In a water going line carrier of the type having a tubular body providing a sealed chamber confining an electric motor, batteries in circuit with the motor and a normally open switch in said circuit for controlling the latter; a resilient rudder at the aft end of said tubular body, a drive shaft housing at the fore end of said tubular body, a propeller at the fore end of said housing, a drive shaft connected to said propeller and said motor, a programmer in said chamber comprising a step-up

mechanism including a cam movable into and out of engagement with said switch for closing and opening the same, a manually operated control line extending into said chamber and secured to said step-up mechanism for advancing the same, tiller arms on said step-up mechanism spaced circumferentially of each other and from said cam for alternately engaging and disengaging said resilient rudder for flexing the same to right and left alternately for changing the course of said water going carrier, said drive shaft housing having a curved contour diverging relative to the fore to aft axis of said tubular body for counteracting torque created by said propeller.

14. In a water going line carrier of the type having a tubular body providing a sealed chamber confining an electric motor, batteries in circuit with the motor and a normally open switch in said circuit for controlling the latter; a resilient rudder at the aft end of said tubular body, a drive shaft housing at the fore end of said tubular body, a propeller at the fore end of said housing, a drive shaft connected to said propeller and said motor, a programmer in said chamber comprising a step-up mechanism including a cam movable into and out of engagement with said switch for closing and opening the same, a manually operated control line extending into said chamber and secured to said step-up mechanism for advancing the same, tiller arms on said step-up mechanism spaced circumferentially of each other and from said cam for alternately engaging and disengaging said resilient rudder for flexing the same to right and left alternately for changing the course of said water going carrier, said drive shaft housing being turnable relative to said tubular body facilitating setting of the curved contour of said drive shaft housing to compensate for drift and side currents in the water in which said vessel is traveling.

15. In a water going line carrier of the propeller driven type having a tubular body providing a sealed chamber confining a motor and a battery in a circuit with a switch for controlling said circuit; a resilient rudder, a programmer within said chamber comprising a ratchet having a segmental cam operatively engageable with said switch for opening and closing the same, a left and a right tiller arm on said ratchet each spaced segmentally from each other and from said cam and alternately engageable with said rudder for flexing the same to the left and to the right respectively, a spring urged pawl for advancing said ratchet in segmental steps, a manually operated control line extending into said chamber and secured to said pawl for pulling the latter against the action of its spring for advancing said ratchet, a drive shaft housing projecting forwardly from said tubular body including a passage, a propeller at the fore end of said housing, and a drive shaft connecting said propeller to said motor comprising a twisted cable snugly fit within said passage whereby the helical trend of said cable cooperates with the internal wall of said passage to force incoming water outwardly of said passage during rotation of said cable.

16. In a water going line carrier of the propeller driven type having a tubular body providing a sealed chamber confining a motor and a battery in a circuit with a switch for controlling said circuit; a resilient rudder, a programmer within said chamber comprising a ratchet having a segmental cam operatively engageable with said switch for opening and closing the same, a left and a right tiller arm on said ratchet each spaced segmentally from each other and from said cam and alternately engageable with said rudder for flexing the same to the left and to the right respectively, a spring urged pawl for advancing said ratchet in segmental steps, a manually operated control line extending into said chamber and secured to said pawl for pulling the latter against the action of its spring for advancing said ratchet, a drive shaft housing projecting forwardly from said tubular body including a passage, a propeller at the fore end of said housing, a drive shaft connecting said propeller to

said motor comprising a twisted cable snugly fit within said passage whereby the helical trend of said cable cooperates with the internal wall of said passage to force incoming water outwardly of said passage during rotation of said cable, said drive shaft housing having a curved contour diverging relative to the fore to aft axis of said tubular body for counteracting torque created by said propeller.

17. In a water going line carrier of the propeller driven type having a tubular body providing a sealed chamber confining a motor and a battery in a circuit with a switch for controlling said circuit; a resilient rudder, a programmer within said chamber comprising a ratchet having a segmental cam operatively engageable with said switch for opening and closing the same, a left and a right tiller arm on said ratchet each spaced segmentally from each other and from said cam and alternately engageable with said rudder for flexing the same to the left and to the right respectively, a spring urged pawl for advancing said ratchet in segmental steps, a manually operated control line extending into said chamber and secured to said pawl for pulling the latter against the action of its spring for advancing said ratchet, a drive shaft housing projecting forwardly from said tubular body including a passage, a propeller at the fore end of said housing, and a drive shaft connecting said propeller to said motor comprising a twisted cable snugly fit within said passage whereby the helical trend of said cable cooperates with the internal wall of said passage to force incoming water outwardly of said passage during rotation of said cable, said drive shaft housing being turnable relative to said tubular body facilitating setting of the curved contour of said drive shaft housing to compensate for drift and side currents in the water in which said vessel is traveling.

18. In a water going line carrier of the propeller driven type having a tubular body providing a sealed chamber confining a motor and a battery in a circuit with a switch for controlling said circuit; a programmer within said chamber comprising a step-up mechanism having cam means alternately engageable with said switch for opening and closing the same, a manually operated control line extending into said chamber and secured to said step-up mechanism for advancing the same, and a brake mechanism on said tubular body facilitating unrestricted forward movement thereof under the influence of said propeller and resisting backward movement of said body when pulled rearwardly upon manipulation of said control line.

19. In a water going line carrier of the propeller driven vessel type having the form of a sealed chamber confining a motor connected to the propeller and a battery in a circuit with the motor including a switch for controlling said circuit; a programmer within said chamber comprising a ratchet having cam means operatively engaging said switch for opening and closing the same, a spring urged pawl for advancing said ratchet in steps, a manually operated control line entering the chamber of said vessel and secured to said pawl for pulling the latter against the action of its spring for advancing said ratchet, a keel-like fin on said body and a baffle plate hinged on said tubular body transversely of said keel-like fin and free to glide through the water during forward movement of said body under the influence of said propeller and for abutting the aft end of said keel-like fin for resisting backward movement of said body when the latter is pulled rearwardly upon manipulation of said control line.

20. In a water going line carrier of the type having a tubular body providing a sealed chamber confining an electric motor, batteries in circuit with the motor and a switch in said circuit for controlling the latter; a resilient rudder at the aft end of said tubular body, a propeller at the fore end of said tubular body connected to said motor, a programmer in said chamber comprising a step-up mechanism including a cam engageable with said switch for opening and closing the same, a manually op-

erated control line extending into said chamber and secured to said step-up mechanism for advancing the same to thereby engage and disengage said cam with said switch at the option of the user manipulating said control line, tiller arms on said step-up mechanism spaced circumferentially of each other for alternately engaging and disengaging said resilient rudder for flexing the same to right and left alternately for changing the course of said water going carrier, a stabilizing keel-like fin on said body set at an angle of at least 5 degrees off vertical to counteract torque created by said propeller, and a baffle plate hinged

5

on said tubular body transversely of said keel-like fin and free to glide through the water during forward movement of said body under the influence of said propeller and for abutting the aft end of said keel-like fin for resisting backward movement of said body when the latter is pulled rearwardly upon manipulation of said control line.
